UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

ELECTRIC CONTROL SYSTEM.

Application filed May 28, 1919. Serial No. 300,455.

To all whom it may concern:

Be it known that I, CHARLES W. WYMAN, a citizen of the United States, residing at Claremont, in the county of Sullivan and

5 State of New Hampshire, have invented certain new and useful Improvements in Electric Control Systems, of which the following is a full, clear, and exact specification.

10 My invention relates to electric control systems.

15 It has for its object to provide an improved electric control system. A further object of my invention is to provide an improved controller mechanism having provision for insuring proper operation thereof and minimizing arcing and burning of the controller contacts. More specifically, my invention has for its object to provide an improved electric control system especially 20 adapted to motor control whereby an operator is required to operate the controller in an improved sequence in such a manner as to avoid the injurious effects mentioned, and one wherein the circuit is controlled by 25 improved means and made or broken in an improved manner. These and other objects and advantages of my improved construction will, however, hereinafter more fully appear.

30 In the accompanying drawings I have shown for purposes of illustration three embodiments which my invention may assume in practice.

In these drawings,—

35 Fig. 1 is a plan view of the controller per se.

Fig. 2 is a detail sectional view taken on line 2—2 of Fig. 1.

40 Fig. 3 is a wiring diagram showing the controller handle in a plurality of positions.

Fig. 4 is a wiring diagram showing a modified form of my invention.

45 Fig. 5 is a wiring diagram showing a further modified form of the same.

In this illustrative construction I have shown a controller including a usual base or panel 1 having pivotally mounted thereon, as at 2, a controller handle or arm 3 adapted to be moved between an "off" stop 4 and an "on" stop 5 to establish electrical connection between the pivot 2 and a plurality of contacts or buttons 6, arranged in the usual arc, of which the first three are

as usual dead and formed of insulating material, while the remainder are live and formed of conducting material.

In my improved construction it will be observed that I have provided improved interlocking or controlling mechanism opera-

tively connected to and controlled by and controlling the handle 3. These means may, obviously, assume various forms. In the form of my invention shown in Fig. 1, the

same include an arcuate member or sector 55 65

7 carried on the panel 1 and struck from the pivot 2, and improved cooperating interlocking mechanism between the member 7 and the controller handle 3. This member 7

is preferably formed of a strip of conducting material set on edge on the panel 1 and between the pivot 2 and contacts 6, as shown.

Herein, the same is also flanged longitudinally on its lower edge, as at 8, and slideable in both directions within correspondingly slotted uprights 9 formed on an arcuate bottom casting 10 carried on the panel,

movement of the member 7 in one direction being limited by a pin 11. It will also be observed that the controller handle 3 carries

70 75 80

on the under side of the same a plurality of sector gripping contact members, herein for illustrative purposes shown in the form of members 12 pivoted at 13 thereon and ex-

tending laterally slightly beyond the controller handle when the latter is in "off" 85

position and toward the member 7. As shown, these members 12 are preferably 90

movable about their pivots on the handle 3 within limits established by a suitable stop 14 on the latter, and are provided with in-

wardly extending gripping contact faces 15 in the form of jaws preferably adapted 95

when inoperative to be held in contact with said stop member 14, or when operative to 100

beheld in gripping contact with the opposite sides of the member 7 by resilient means, herein in the form of a coiled spring 16, operatively disposed in recesses 17 in the

two members 12, though obviously the de- 105

sired resiliency may be otherwise incorporated in these contact members. It will also be observed that I have provided a recessed or slotted portion 18 substantially midway between the ends of the member 7, herein in the form of a rectangular cut-out portion in its lower edge, which is adapted to receive and have its end walls engage with

an arm 19 formed on a bell crank circuit controlling member 20 pivoted at 21 on a rearward extension 22 on the member 10, and having a lower contact arm 23 adapted to 5 make and break a circuit at a contact button 24 disposed between the pivot 2 and the articulate member 7. Thus, it will be observed that when the member 3 is moved toward "on" position its gripping contacts 15 will 10 grip and move the member 7 therewith, and that when the arm 3 is moved backward, that is, toward "off" position, the member 7 will likewise be moved therewith so that the arm 23 will be moved off of its contact 15 button 24 through the engagement of one end wall of the cut-out portion 18 with its member 19.

Attention is also directed to the fact that improved cooperating operative connections 20 are herein provided between the member 20 and the controller handle or arm 3 to control the movement of the contact arm 23. These connections may, obviously, likewise assume various forms. Herein, it will be observed 25 that a slot 25 is provided in a downwardly projecting hub of the arm 3 and near the pivot thereof, the end wall of which is adapted to engage the free end of a strip 26, preferably formed of insulating material, which 30 is itself operatively connected to the member 20, as by pivoting the same around a laterally off-set upright pin 27 on and near the pivot thereof. It will also be observed that I have provided a guiding means for said 35 strip 26, herein in the form of a U-shaped spring 28 having one end fixed to the member 26 and its other end slidably in the slotted upper end of a pin 29, herein formed on a rearward extension 30 on the casting 10, 40 the construction being such that the spring thereby assists in locating the strip 26 relative to the slot 25 during movement of the parts. As a result of this improved construction, it will be noted that during the 45 last stages of the movement of the arm 3 toward "off" position, the contact arm 23 is thrown into engagement with the button 24, and that thereafter during current flow whenever the arm 3 is moved toward "off" position, the contact arm 23 is disengaged from its button.

Operatively connected to the contact 24 and controlled by the moving contact arm 23 and the movement of the controller arm 3, 55 is improved cooperating circuit controlling means. These means, as shown herein, assume the form of an electro-responsive switch, herein in the form of a solenoid 31 carrying a movable contact bridging member 32 adapted to bridge contacts 33 disposed in one of the branches of the line 34, 34', the solenoid herein being connected to the line conductor 34 at a point outside the contacts 33 by a conductor 35 which is in turn 60 connected to the contact 24. As shown, the

motor, which may be of any suitable type, herein of the compound wound type including an armature 36, a shunt field 37, and a series field 38, is herein connected inside the contacts 33 and to the various resistance sections 39 connected to the resistance buttons 6, by means of a conductor 40. Thus, it will be observed that after the contact arm 23 is moved into engagement with the contact 24, i. e., as the controller arm 3 75 moves into "off" position, and when the arm 3 is again moved forward in such a manner as to bring its contacts 12 into engagement with the sector 7, a circuit is established from the line 34 through the coil of the 80 electro-responsive switch 31, the conductor 35, the contact 24, the contact arm 23, the sector 7, the contacts 12, the arm 3, and the arm pivot 2, to the other line conductor 34' in such a manner as to cause the contact bridging member 32 of the electro-responsive switch to bridge the contacts 33 and thereby close the line circuit, whereupon, when the arm 3 is moved still further forward, current flows through the armature and fields 85 of the motor in the usual manner, and through so much of the resistance 39 as then remains in circuit. Conversely, it will be observed that when the arm 3 is first moved backward or toward "off" position from any 90 position, current flow through the motor will be immediately interrupted due to the break in the circuit of the electro-responsive switch, and not be reestablished until the arm 3 has moved off of the contacts 6 and 95 practically reached its "off" position, when the contact arm 23 will be again actuated to close the contacts 23, 24.

In the operation of my improved controlling system and mechanism, it will be observed that the electro-responsive switch is 100 normally open, and this in spite of the fact that the contact arm 23 in the "off" position of the controller arm engages with its contact 24, the contacts 12 then being out of engagement with the sector 7. However, as soon as the arm 3 is moved toward "on" position sufficiently to bring these contacts 12 into engagement with the sector 7, current flow is established through the electro-responsive switch as above set forth, in such a 105 manner as to actuate that switch and thereby close the contacts 33. Current, however, does not flow through the motor until the controller arm 3 engages with the first live button 6, when the normal current flow through the motor is established, the resistance 39 being progressively cut out as the arm 3 moves toward "on" position. Obviously, this movement toward "on" position is in no way retarded. However, if the operator, after advancing the controller arm over less than the total number of live contacts 6, reverses the movement of the controller arm 3, it will 110 be observed that through the gripping ac- 115

tion of the contacts 12 upon the sector 7, the latter will be moved toward "off" position with the controller arm 3, and through the engagement of one of the end walls of its cut-out portion 18 thereby cause the contact arm 23 to be moved off of its contact 24 in such a manner as to break the circuit through the electro-responsive switch 31 and thus cut out the motor. It will also be observed that after the circuit has thus been broken, the operator is powerless to reestablish circuit connections by continuing the movement of the controller arm 3 toward "on" position until he has first moved the latter back to full "off" position. During this movement, moreover, it will be observed that after the arm 3 has passed off of the first live button 6, the end of the slot 25 will engage with the strip 26 in such a manner as to cause the same, acting through its connection to the pin 27, to swing the contact arm 23 again into contact with its button 24. In other words, it will be observed that the initial position of the parts is then resumed so that the operator may again move the controller arm toward "on" position.

Referring to Fig. 4 of the drawings, it will be noted that herein I have illustrated a modified form of my improved construction wherein, instead of having the current flow through the sector as described above when the circuit through the electro-responsive switch 31 is closed, the circuit extends from the contact arm 23 through its pivot 21 and a conductor 41 directly to the pivot 2, which is connected to the other side of the line. As a result of this connection, it will be observed that the gripping members 12 and sectors 7 serve simply as a part of the operating mechanism, as distinguished from a part of the operating mechanism and also a part of the electrical circuit, a desirable feature under certain conditions. It will also be observed that the connection necessary thus to simplify the circuit connections is itself exceedingly simple, it only being necessary to connect a wire between the two pivots 21 and 2. Here it will also be noted that I have illustrated a modified form of circuit connections, the shunt field winding 37 being connected in shunt with a permanent or grid resistance 42 to the conductor 35, an arrangement having decided value when operating on high voltages.

In Fig. 5, it will be observed that I have illustrated a further modified form of wiring connection adapted to use in connection with either form of my improved controller described above when a reverse switch is used. Herein, it will be observed that instead of having the contacts 33 disposed outside the point of connection of the shunt field 37, these contacts are disposed between the point of connection of the shunt field to

the line conductor 34, on the one hand, and the series field on the other, while the electro-responsive switch included in the connection 35 is connected to the conductor 34 at the same point as the shunt field. Through this arrangement it will be observed that the shunt field is not in circuit with the armature, which may be revolving but not generating current, and that a reverse switch 43 may accordingly be moved without the arcing or burning experienced if the shunt field is connected as in Fig. 4. It will, however, be evident that various other modifications of the wiring connections may be made in various adaptations of my invention. It will also be evident that when and where desired the usual supplementary controlling devices, such as a reversing switch 43 and a fuse 44, may be included as needed in the wiring connections and used in connection with any of the forms of my invention shown herein.

As a result of my improved construction, it will be observed that the entire electrical system including the controller system and the motor, is protected from abuse by ignorant operators, my improved construction making it impossible for an operator to move the controller back and forth over the resistance contacts without allowing a proper interval between these reverse operations thereof. More particularly, it will be observed that through my improved construction an interval is necessarily provided between a reverse movement of the controller handle and a forward movement thereof, since the operator must return the controller handle to "off" position before he can again establish electrical connection and obtain any results through moving the controller arm further toward "on" position. Attention is also directed to the fact that through my improved construction including the electro-responsive switch, it is possible to make or break the circuit connection at a point other than at the controller contacts, thereby minimizing the arcing and burning of the latter. It will also be observed that through this same feature of my invention it is possible to connect the electro-responsive switch at any desired point in the system, it being entirely immaterial, so far as the broad aspects of the invention are concerned, whether the same is located directly adjacent the controlling mechanism or at a point remote therefrom, a feature of decided importance in certain service. These and other advantages of my improved construction and arrangement will be, however, clearly apparent to those skilled in this art.

While I have in this application specifically described several forms which my invention may assume in practice, it will be understood that these forms are used for purposes of illustration and that the invention

tion is not limited thereto but may be modified and embodied in various other forms without departing from its spirit.

What I claim as new and desire to secure by Letters Patent is:

1. In an electric controller, a controller arm, engaging means carried thereby and supplemental circuit closing means successively actuated in opposite directions by said engaging means as said arm moves in one direction.

2. In an electric controller, a controller arm, circuit closing means successively opened and closed thereby as said arm moves in one direction and means for retaining said closed position when moved in the opposite direction.

3. In an electric controller, a controller arm, and circuit controlling means opened upon "off" movement of said arm and closed as said arm approaches "off" position, and inoperative when moved in the opposite direction.

4. In an electric controller, a controller arm, having "off" and "on" positions engaging means carried thereby, and supplemental circuit closing means successively actuated in opposite directions by said engaging means as said arm moves in one direction, said circuit closing means being substantially instantly actuated on reverse movement of said arm from any "on" position thereof.

5. In an electric controller, a controller arm, circuit closing means successively opened and closed thereby as said arm moves in one direction, and means for retaining said closed position when moved in the opposite direction, said means including reciprocable means.

6. In an electric controller, a controller arm, circuit controlling means, and means whereby said latter means is opened on "off" movement of said arm and closed as said arm approaches "off" position, and inoperative when moved in the opposite direction, said last mentioned means including a plurality of cooperating uniformly engaged operating members during closing of said circuit closing means.

7. In an electric controller, resistance controlling means including a movable controller member, a sector, means for moving the latter in only one effective direction with said member, and a supplemental switch cooperating with said sector and having a lost motion connection therewith.

8. In an electric controller, resistance controlling means including a controller arm, a supplementary switch, a switch actuating member, and gripping means carried by said controller arm and engageable with said switch actuating member.

9. In an electric controller, resistance controlling means including a controller arm,

a supplementary switch, a switch actuating member, and contact means carried by said arm engageable with said actuating member to actuate the latter.

10. In an electric controller, resistance controlling means including a controller arm, a supplemental switch, a switch actuating member engageable therewith, means for establishing electrical connection through the supplemental switch and said actuating member, and means for actuating said member.

11. In an electric controller, resistance controlling means including a controller arm, a plurality of contacts engageable thereby, a supplemental switch including said controller arm and electrically connected thereto, and means for successively actuating said switch as said arm is moved in one direction relative to said contacts.

12. In an electric controller, resistance controlling means including a controller arm, a plurality of contacts engageable thereby, a supplemental switch including said controller arm and electrically connected thereto and means for opening and closing said switch as said arm is moved toward "off" position when beyond the first contact.

13. In an electric controller, resistance controlling means including a controller arm, and means including said controller arm for breaking an electric circuit connected therethrough upon reverse movement of said arm and reconnecting the circuit connections when said arm is moved to "off" position.

14. In an electric controlling device, controlling means comprising a controller arm, and a plurality of switches controlled by said controller arm, both of said switches being opened and one of said switches being reclosed by said member during the movement thereof in one direction.

15. In an electric controlling device, a controlling means comprising a controller arm and a plurality of switches in series controlled by said controller arm, said switches all being simultaneously in closed position during "on" movement of said controller arm and then successively opened by said controller member on "off" movement thereof.

16. In an electric controlling device, controlling means comprising a controller member, a plurality of switches in series during entire movement of said controlling means in one direction controlled by said controller member, and means whereby the opening of one of said switches necessitates the opening of the other prior to the closure of said first named switch.

17. In an electric controlling device, controlling means comprising a controller member, a plurality of switches in series during

entire movement of said controller from "off" to "on" and controlled by said controller member, one of said switches being mechanically actuated by said controller member, and means whereby the opening of said last mentioned switch necessitates the movement of said member to off position prior to its reclosure.

18. In an electric controller, controlling means, a plurality of controlling switches, means whereby said switches are kept in series during entire unidirectional movement of said controlling means, means for opening one of said switches, and means to close the same by a continuation of a movement to open the other.

19. In an electric circuit controlling mechanism including a controller, and a pair of switches, one of said switches comprising a member operative when moving in one direction to positively open and close the other thereof.

20. In an electric controlling mechanism, comprising a plurality of switches each having a plurality of relatively movable elements, both elements of one of said switches being movable and so arranged that the movement of each of said elements in one direction will cause a reversal of the position of one of the elements of the other switch.

21. In an electric circuit controlling

mechanism, comprising a controller member, and a plurality of switches in series during entire movement from "off" to "on" and controlled by said controller member, different switches in said plurality being closed upon movement of said controller member in different directions.

22. In an electric circuit controlling mechanism, a controller member, and a plurality of switches in series during entire movement of said controller from "off" to "on" and controlled by said controller member, one of which switches is closed at the beginning of the movement of said controller member in one direction and the other of which is closed at the end of the opposite movement thereof.

23. In an electric circuit controlling mechanism, a controller member, and a plurality of switches in series during entire movement of said controller from "off" to "on" and controlled by said controller member, one of which switches is closed at the beginning of the movement of said controller member to full running position and the other of which is closed by said controller member at the end of the off movement of said controller member and after said first mentioned switch has been opened.

In testimony whereof I affix my signature.
CHARLES W. WYMAN.
